SINGLE SPINDLE AUTOMATIC MACHINE

Alfred E. Drissner and Kenneth W. Barkinen,
Cleveland, Ohio, assignors to The National
Acme Company, Cleveland, Ohio, a corporation
of Ohio

Application November 14, 1939, Serial No. 304,319

30 Claims. (Cl. 29—41)

1

This invention relates to what are commonly designated as single spindle automatic screw machines, an object of the invention being to provide an improved machine of this type which may be used as a bar machine in which the stock bar is fed through the spindle as in multiple spindle machines or as a chucking machine wherein castings, forgings and the like may be held in a chuck located on the front end of the spindle as in multiple spindle chucking machines, one of the principal objects of the invention being to provide a machine of this type in which many of the mechanisms are hydraulically operated with high speed and accuracy.

Another object of the invention is the provision of an improved machine of this type in which the indexing of the end tool slide turret and the unlocking of the turret is controlled and operated by hydraulic means and in which the several reciprocating slides of that turret are likewise controlled and operated by hydraulic means as is also the top cross slide of the machine, and in which the chucking means and return of the stock feed slide are also controlled by hydraulic means, the machine also having fluid controlled means for operating the high and low speed clutch and spindle clutch.

Still another object of the invention is the provision of a low-type, compact, sturdy single spindle machine having a capacity up to approximately 10" diameter stock and in which all of the operating mechanisms are completely enclosed and protected from dust and dirt and readily accessible to the operator at both sides of the machine and which may be considered as having the same relation to former types of single spindle machines as the present stream-lined automobile has to that of the early 1900's. In short, there is provided an improved single spindle screw machine so constructed that it has a number of the important features heretofore thought possible only in the present multiple spindle machines and whereby this improved single spindle machine will have a larger range of production and greater capabilities of use than has such machines heretofore, and in which the work spindle and the indexable tool turret are both located substantially centrally lengthwise of the machine with their axes in parallelism in the same plane, thus enabling the building therearound of numerous important improvements readily accessible from either side while insuring a low, compact machine capable of more economical production than has been possible on single spindle type machines.

In machines of this type, the single stock carrying spindle is rotated while the tool carrying turret is indexed and the several tool carrying slides thereof are reciprocated toward and from the work, the side cross and top tools being car-

2

ried by cross and top slides and the present improved construction is such that the machine may be carried in a pan adapted to hold a large amount of cutting oil and having a large chip space under the main turret slide communicating with a chip clearance passage of ample capacity for easily removing the chips without stopping the machine and facilitating the use of a chip conveyor when required.

In the drawings accompanying and forming a part of this specification,

Fig. 29 is a side elevation of the left hand cross slide shown in Figs. 1, 2 and 4.

Fig. 30 is a side view partly in section of the hydraulic valve control mechanism.

Fig. 31 is a cross section taken on line 31—31 of Fig. 30, and

Fig. 32 is a diagrammatic view of the hydraulic pistons and controlling valves therefor and including the motor pump and reservoir.

Similar characters of reference indicate corresponding parts in the several views.

Before explaining in detail the present improvement and mode of operation thereof, we desire to have it understood that the invention is not limited to the details of construction and arrangement of parts illustrated in the accompanying drawings since the invention is capable of other embodiments, and that the phraseology employed is for the purpose of description and not of limitation.

General description

Referring to Fig. 1, this improved single spindle machine comprises a pan-shaped base 1 adapted to carry the entire machine having a framework or housing consisting of a gear box housing 2, an end tool turret index mechanism housing 3 and a feeding and chucking mechanism housing 4 in which are located the main drive motor 5 at the rear side thereof and the hydraulic motor 6, pump 8 and hydraulic and lubricating oil reservoir 7 at the front side thereof.

Supported at one end by the turret index mechanism housing 3 and at its other by the main frame is the indexable slide support 8 for the four main turret slides 9 shifted individually when indexed in line with the spindle by hydraulic means and the feeds of which may be varied.

A rear side cross slide 10 angularly mounted, a front side cross slide 11 horizontally mounted and a top slide 12 for the side tools are supported around the work spindle 21 in front of the gear box housing 2 and located above the rear cross slide are spindle change gears 13. Located on the rear wall of the gear box housing 2 are feed change gears, hereinafter referred to, for the two side cross slides which are cam and lever operated, whereby various feeds may be given these two slides, the different feeds of the top slide which is fluid operated being obtained by means of a fluid controlling valve. These three slides are of very heavy construction to withstand exceptionally coarse feeds of the forming and cutting off tools.

Located in the tool turret index housing 3 is the hydraulic motor 15, hereinafter referred to, and in this same turret housing is located the turret lock bolt mechanism 16. At both sides of the turret and extending above the pan are chip guards 17 between which ample chip and cutting oil space 18 is provided communicating with a chip clean out passage 20 also of ample size. It

will be observed (see Fig. 1) that the end housing supporting frame 3 is arch-formed, thereby providing an enlarged chip clean-out passage or opening 20 so that the chips may be readily removed from the end of the machine without the necessity of stopping the machine, as heretofore, in order to remove the chips at the sides thereof. At one side of the spindle and carried by the housing is an auxiliary support 18 for an additional tool attachment.

Encircled by the cross and top slides is the rotary work spindle 21, rotatable in either direction, and carried by the corner of the square turret slide support is a suitable stock stop 22, and it will be observed that the end tool turret or tool slide carrier is located below the center of the work spindle and comprises independent tool slides operated from within the turret for carrying the end working tools and that it is not a round turret or one located above the center of the work spindle as in certain old machines.

As before stated, the machine is adapted for use as a bar machine but has a removable nose piece 9 (see Fig. 5) on the spindle adapted for attachment of a chuck so that the machine may be used as a chucking machine. When used as a chucking machine, the collet and feed tubes are removed.

The indexing mechanism for the tool turret and the locking thereof are hydraulically controlled independently from the forming and cut-off slides. The turret slides are also controlled hydraulically with independent controlling means for fast and slow speed of each independent turret slide.

The front and rear forming slides are controlled by independent cams which will permit continuous forming while the turret slides advance, return and index, so that this entirely separates the end working tools from the forming tools carried by the cross slides. This is very desirable especially on work where the forming operation takes longer and several different types of end working tools are necessary to complete work during the actual forming time.

A cut-off slide can be mounted on the machine and used as an independent attachment and may have its own independent controlling means but where this is not needed the rear forming slide can be used as a cut-off slide.

The chucking mechanism is likewise completely hydraulically controlled and the stock feed mechanism is timed with the chucking mechanism so that no extra cams and mechanism are required to adjust and time the feeding device for the stock.

By having the large chip space directly under the turret slide whereby the chips can be removed from the front of the machine through the chip clean-out passage, this eliminates the down time for the machine while removing the chips, that is to say, the chips can be removed without stopping the machine and also provides a means, as hereinbefore stated, for the chip conveyor when required and an especially large bottom surface for the cooling and cutting oil.

The main motor 5, mounted at the rear end side of the machine, is adjustable and completely housed so that it does not obstruct the top and general design of the machine and this is also true of the hydraulic pump motor 6 and pump 8 whereby they are easily accessible by merely removing the cover and the general construction of the machine is such that all necessary piping for the hydraulic mechanism is completely enclosed

and thus not exposed to chips or parts cut off from the stock bars.

The hydraulic pressure necessary for the operation of the various mechanisms hereinbefore referred to, is obtained from the hydraulic pump motor 6 and pump 6'. The pump 6' draws oil from the reservoir 7 and this supplies the entire hydraulic system with the required oil pressure and, by means of the proper valves in the hydraulic system, oil is directed to the pistons which actuate the various parts. This oil then passes back through these valves to the reservoir 7, thereby completing the hydraulic oil circuit.

A diagrammatic lay-out of this hydraulic system is shown in Fig. 32 which bears certain indicia to facilitate the reading thereof, and Figs. 30 and 31 illustrate the control valve mechanisms.

Main or spindle driving mechanism

Referring to Figs. 3, 5, 6 and 7, the main driving motor 5 is secured to a swivel base 23 swinging on the shaft 24 and is adjustable for proper chain tension by a bolt 25 and nut 26. The bolt is secured by a pin 27 in lugs cast integral with the pan while the shaft 24 is secured in lugs likewise integral with the pan. This drive motor 5 is provided with a sprocket 28 carrying a driving chain 29 leading to a sprocket 30 on one end of the main driving shaft 31 supported in anti-friction bearings, which drive shaft 31 on its opposite end carries a spindle change gear 32 meshing with a change gear 33 on the shaft 34 supported in anti-friction bearings and carrying at its opposite end the gear 35 meshing with a gear 36 on a shaft 37 supported in anti-friction bearings. This gear 36 meshes with a gear 38 carried by the rotary work spindle 21 mounted in anti-friction bearings and by means of which this spindle is rotated by a straight drive.

This spindle is provided with a nose piece S (see Fig. 5) when the machine is used as a bar machine and when used as a chucking machine, this nose piece S is removed so that a chuck can be applied. The conventional spindle nose may be used (when not required to provide means for change over to chucking machine) with the usual bar feeding means comprising finger holding mechanism T (see Fig. 5), feed tube U, pusher V, nut and bushing W, collet tube X, collet tube nut Y and collet Z. This finger holding mechanism has a double toggle member B9, the two levers of which are connected at their inner ends to a roller. The outer ends of the levers are received in socketed members, the distance between the opposing faces of which socketed members, when shifted toward each other, is but slightly greater than the diameter of the roller, thereby permitting the use of this toggle in a small compact space without affecting the efficiency thereof and this result is obtained by reason of the fact that the diameter of the roller and length of the levers are all so proportioned and constructed relative one to the other that the relatively shiftable socketed members may very closely approach each other and yet have considerable longitudinal movement to exert great pressure on the chucks or collets with but slight movement of the operating means therefor. By means of this double toggle, movement of the collet is increased with no additional movement of its sleeve with the result that the machine will handle more satisfactorily the extreme diametrical variations which prevail in large sizes of hot-rolled or rough bar stock.

If it is desired that the work spindle 21 have

a greater range of spindle speeds so that two spindle speeds can be used to save time as when cutting on large O. D. of work, one spindle speed would be used and when the O. D. of the work becomes smaller and a higher spindle speed could be used, the shaft 34 is provided with a disk clutch 39 (see Fig. 6) hydraulically operated so as to drive through one or the other sets of gears 35 and 36 or 41 and 40.

10 This clutch 39 is operated by a hydraulic piston 42 (see Figs. 26 and 27) operating the usual clutch shifter fork 43 carried by a shaft 44 suitably supported by the framework at one end.

The piston 42 is operated as the oil from the pressure line passes through the valve V1 to one end of the piston 42. As the piston moves, oil from the opposite end is discharged back through the valve V1 and thence to the reservoir 7 (see Fig. 32).

15 This procedure is reversed to shift the clutch 39 in the opposite direction.

20 The work spindle may be rotated in either direction. For the purpose of reversing the spindle, an idler gear 45 (see Figs. 6 and 7) is used between the shafts 34 and 37, this idler gear rotating on a stud 46 secured to the framework and substituting a gear 41' (see Fig. 7) for the gear 41 (see Fig. 6).

Cross slide driving mechanism

25 30 As before stated, the top slide 12 is hydraulically operated but the two side cross slides 10 and 11 are driven by lever and cam mechanism and for this purpose the shaft 34 has at one end thereof a gear 47 (see Figs. 3, 5 and 6) which drives the gear 48 mounted on a worm shaft 49 (see Figs. 2, 3, 16 and 17) and this worm shaft, by means of its worm, drives a worm wheel 50 secured to a disk clutch 51 mounted on a shaft 52. This disk clutch is engaged when the machine is operating at low speed and disengaged when operating at high speed, as while indexing, and this clutch is actuated hydraulically, as will be herein-after explained.

35 40 This shaft 52 carries the feed change gear 53 driving the feed change gear 54 on a worm shaft 55, which worm shaft drives the worm gear 56 carried by a cam shaft 57. The worm gear 56 is provided with a friction drive safety 58 (see Fig. 16).

45 50 The worm shafts 49 and 55 with which the worms are integral, together with the shaft 52, are mounted in anti-friction bearings.

55 60 The cam shaft 57 is mounted in sleeve bearings and carries a cam disk 59 provided with cams 60 by which the rear cross slide 10 is operated by the lever 61. To this cam disk 59 is secured a gear 62 driving an idler gear 63 mounted on a stationary shaft 64 supported in the housing at three points and held in place by a dog point screw in a spacer 65 (see Fig. 24). This gear 63 drives a gear 66 (see Figs. 2 and 3) secured to a cam disk 67 mounted on a shaft 68 mounted in sleeve bearings. Similar cams secured to this cam disk 67 operate the front cross slide by means of a lever 70.

65 70 The front and rear cross slides 10 and 11 are mounted on hardened steel angle plates 71 (see Fig. 29) secured to the frame and provided with adjustable gibs 72. The cross slide pusher 73 is dovetailed to the cross slide and fastened thereto by a wedge 74. By this means, the cross slide can be adjusted for proper tooling. The cross slide operating levers are connected to the pusher 75 73.

7
Top slide

The top slide 12 (see Figs. 2, 4, 8 and 28) operates in a bracket 15 having a dovetailed base secured to the framework by a gib 16 (see Fig. 4) by which means adjustment of the top slide and its bracket longitudinally along the spindle axis is obtained when desired. Reciprocating movement of this slide is accomplished by a gear segment lever 17 operated by a hydraulic piston 18. This top slide 12 is provided with spring cushions 19 and slide adjusting gib 20.

The piston 18 is operated as oil from the pressure line passes through the valve V8 (see Fig. 32) to one end of the piston 18. As the piston moves, oil from the opposite end is discharged and passes through the feed regulator valve V9 which is mounted at the side of the slide bracket 15 (see Fig. 9) and then back through the valve V8 to the reservoir 7.

This procedure is reversed to move the slide in the opposite direction. The valve V8 is operated by the same mechanism as other valves herein-after referred to.

Secured to the top slide 12 is an adjustable cam 20' (see Fig. 9) and this cam operates a cam roll 20" held in engagement with the cam by a spring 20'", the roll being carried by a rack bar 20"" and by this means the valve V9 is regulated and the feed of the top slide controlled.

Main-turret tool slide mechanism

The turret tool slides 8, shown as four in number (see Figs. 1, 4 and 22) are secured in place by gib 21 and are each individually moved longitudinally along the turret slide support 8 by a yoke 22 (see Fig. 22) in position to engage slide pullers 23 when each slide is in line with the work spindle. The yoke 22 is secured to a pull shaft 24 which does not rotate but is shifted longitudinally by a hydraulic piston 25. This shaft 24 is supported in the turret and prevented from rotating by a guide arm 26, the opposite end of which is supported by the shaft 24 carrying the idler gear 28 operating the cross slide 11 hereinbefore referred to.

The piston 25 is hydraulically operated as follows:

The hydraulic pump 6' (see Figs. 1 and 32) draws oil from the oil reservoir 7 to supply the high pressure line leading from the pump. This oil passes through the valve V6 (see Figs. 30 and 32) to one end of the piston 25. As this piston moves, the oil from the opposite end is being discharged and passes through the feed regulator valve V7' (see Figs. 24 and 32) and back through the valve V6 to the reservoir 7.

This procedure is reversed to move the turret slides in the opposite direction.

The valve V6 is actuated by a lever 27 (see Figs. 30 and 31) fulcrumed on a stud 28 secured to a shaft 29, both ends of which are secured in the framework. The lever 27 is actuated by cams 30 mounted on a drum 31 secured to a shaft 28 and rotatable therewith.

Another shaft 33, supported at both ends in the framework, is provided with guide means 34 for guiding the lever 27. The piston 35 of the valve V6 is operated by this lever 27 through a bell crank link 36, 36' (see Fig. 31) controlled by a spring plunger 200 so as to accelerate movement of the piston 35.

The turret feed regulator valve V7' (see Figs. 24, 25 and 32) is operated by individual cams 37, one for each turret slide, bolted to the sides of

8
a cam slide 38 which is mounted on a shaft 39 supported in the framework parallel to the turret axis. This shaft 39 and slide 38 thereon index with the turret by means of a sprocket 40 driven by a chain 41 from a sprocket 42 on a turret stem 43 (see Fig. 22). Longitudinal movement of the slide 38 is accomplished by the arm 44 fastened to the pull shaft 24 and slidable therewith.

10 This arm 44 is provided with a slot to receive a roller 45 which slides in the slot thereby operating a lever 46 which is provided with two shoes 47 fitting into the spool end of the slide 38, this lever 46 being fulcrumed on a shaft 48 supported on the frame.

Turret indexing and locking mechanism

Referring to Figs. 19, 20 and 21, the tool turret is indexed hydraulically and is locked after each indexing by a lock bolt of the lock bolt mechanism 49.

20 Oil from the hydraulic pump 6', which is controlled by a valve V8' (see Fig. 32) suitably operated from the cam shaft (see Fig. 32) passes through the line 117 to one end of the piston 118 located in a piston cylinder 111 and this piston is in position to engage an adjustable device 112 on the lower end of a pivoted lever 113, the opposite end of which lever is pivoted to the lock bolt 114 and as the piston shifts the lever, the lock bolt is withdrawn from its lock seat 115 carried by a lock bolt disk 116 secured to the turret slide support 8, there being one lock bolt seat for each slide.

25 35 When the lock bolt 114 is completely withdrawn from its seat, the piston 118 has been moved sufficiently to permit the oil from the motor driven pump 6' to pass through the pressure line 115' to the hydraulic motor 15 and thence through the line 117, cylinder 111 and line 109 to the reservoir 7. The movement of this oil thus starts the rotation of the indexing motor 15 located in the tool turret housing 3 and so indexes the turret.

40 45 When the piston is shifted back to close the line 117, it acts as a shut-off valve and stops the flow of oil through the cylinder 111 and this stops the motor 15.

The piston is provided with suitable wedge-shaped grooves to stop the flow of oil gradually and the cylinder may be provided with a diametric groove so that if the piston should turn and the wedge-shaped groove is not directly in alignment with the line 117, the oil passage is nevertheless maintained. A drain 108' leads from the piston cylinder 111 at the opposite side of the piston 118 and its inlet pipe 117' to the line 108.

45 55 The shaft of the indexing motor 15 carries a gear 119 in mesh with the gear 120 which drives the gear 121 carried by the hub thereof which, in turn, drives a gear 122 secured to the lock bolt disk 116 and by this mechanism the turret slide support 8 and the slides 8 are indexed.

50 55 When each turret indexing step is completed, the spring 123 pushes the lock bolt 114 toward the center of the lock bolt disk 116, riding on the surface thereof. This surface tapers toward the center of the lock bolt disk 116 from the point X to the point X' so that, as the lock bolt 114 rides down this tapered surface carrying the lever 113 therewith, the piston 118 is gradually moved, thereby throttling the flow of oil to the motor 15 which slows down the indexing movement of the turret to permit the bolt 114 to drop gently into its seat 115. When the bolt has dropped

into its tapered seat, the piston 110 has moved to its starting position and closes the oil passage to the reservoir 7, thereby stopping the rotation of the motor 5 until it is again ready to index the turret.

Thus, the hydraulic mechanism operates to withdraw the lock bolt and to index the tool turret slides, the bolt being spring actuated into locking position as each slide is indexed into position to have its tool cooperate with the work carried by the rotary spindle. After the oil operates the motor 5, it flows back to the reservoir 7 through the cylinder 111.

Stock feed mechanism

For feeding the stock through the rotary spindle to the tools carried by the indexable turret and by the cross slides and referring to Figs. 3 and 18, a bracket 124 is supported at one end by the main frame and at the other end by a suitable upright 124' and has a plate 125 bolted thereto which supports a guide plate 126. This plate 126 guides a feed slide 127 and has a runway on each side to receive rolls 128, four in number, carried by the slide 127.

The feed slide 127 has a pusher 129 bolted thereto which slides along in a slot in the guide plate 126. This pusher is tapped to receive a hydraulically operated piston 130 which, acting against the pusher 129, returns the feed slide 127, at the same time compressing the feed spring 131 so that when the hydraulic pressure is released on the piston 130, this spring drives the slide 127 forward to feed the stock.

The spring 131 is housed in a tube 132 which is screwed into the end of the plate 126. This spring is also guided on a rod 133 which is secured to the pusher 129 and moves therewith.

To regulate the length of feed, the backward movement of the slide 127 is controlled by an adjusting stop block 134 and stop screw 135.

To permit the feed tube to be removed, the slide 127 has a hole large enough to permit the feed tube head to pass therethrough and the connection between this slide and tube is made by a feed shoe 136 engaging a slot 137 of the slide 127 and this shoe is connected with the slide 127 by a pin 138 (see Fig. 3) enabling it to be swung out of position to remove the feed tube.

From the foregoing it will therefore be seen that the feeding of the stock is obtained by the spring 131 which, however, is reset hydraulically when the chucking piston hereinafter described is in chucking position, thereby opening the oil passage and permitting the flow of oil through the valve V5 (see Fig. 32) to one end of the piston 130.

When the chucking piston hereinafter referred to returns to the unchucked position, the passage of oil to the piston 130 is closed and the spring 131 feeds the stock and at the same time returns the piston which forces the oil back through the valve V5 to the reservoir 7.

The valve V5 is merely a by-pass valve suitably arranged inside the frame. Oil is admitted to only one end of the piston 130. However, the other end of the piston cylinder is provided with a drain line to the reservoir 7.

Chucking mechanism

Referring to Figs. 3 and 18, a bracket 139 is bolted to the main frame and carries a pin 140 on which the chucking yoke 141 swivels and this yoke carries chucking shoes 142 which fit into a finger holder spool to open and close the chuck.

A square block 143 is held in this yoke 141 by a pin 144 and fits into a slot in the chucking slide 145. This chucking slide 145 is supported and slides on a shaft 146 secured to the frame and this slide is actuated by a hydraulic piston 147 secured thereto by a screw 148.

To provide for hand chucking, the shaft 146 is slotted at one end to receive a hand chucking lever 149 secured to the shaft by a pin 150. A connecting link 151 is pivoted to this hand lever 149 and can be connected to or disconnected from the slide 145 by means of a pin 152.

In operation, the oil from the pressure line passes through the valve V4 to one end of the piston 147 and as the piston moves, the oil from the opposite end is discharged back through the valve V4 to the reservoir 7. This procedure is reversed to actuate the chucking spool in the opposite direction.

20 The valve V4 is operated the same as the valve V6. In fact, the valves V6, V8, V3 and V4 are built as one unit (see Fig. 30), while the valves V6' and V7 are operated from the cam shaft.

High speed or rapid traverse mechanism

25 Referring to Figs. 3 and 10 to 15, inclusive, high and low speed clutches transmit motion through the worm shaft 55 to the cam shaft 57 which operates the two cross slides and various hydraulic valves.

30 The main drive motor 5 transmits motion to the cam shaft 57 through the low speed clutch 51 during the period when the cross slide tools are cutting and during the indexing or rapid traverse period, motion is transmitted to this cam shaft 57 through the high speed clutch 158 from the hydraulic motor pump at a much higher speed so as to reduce the idle time, thereby greatly increasing production.

40 This high speed or rapid traverse is obtained from a double-end shaft 153 (see Figs. 10 and 12) of the motor 6 (see Fig. 32), which motor also drives the hydraulic pump 6'.

45 A coupling 154 on this motor shaft 153 drives through a gear 155 to a gear 156 secured to the high speed shaft 157. A disk clutch 158 is suitably arranged on this shaft 157 and by means of a sprocket 159 and chain 160 drives a sprocket 161 on the worm shaft 55. Proper tension of this 50 chain 160 is obtained by means of an adjustable sprocket 162 carried on a stud 164 mounted in a bracket 163. This bracket 163 is mounted for swinging movement on a flanged bushing 164' through which the shaft 157 extends (see Fig. 10) 55 and is held in position by a nut 164''. The sprocket 162 is adjusted by an adjusting nut 165 carried by a stud 166, the stud and nut being carried by a bracket 167 secured to the frame.

The high speed clutch 158 and low speed clutch 51 (see Fig. 17), hereinbefore referred to, are operated in coordination by a hydraulic piston 169 (see Figs. 15 and 32) which piston, by means of a link 170, is connected to levers 171 and 172 fulcrumed on pins 173 and 174 secured to the frame.

65 The clutches 158 and 51 are thus operated hydraulically when oil from the pressure line passes through the valve V3 (see Fig. 32) to one end of the piston 169 (see Fig. 15). As the piston moves, the oil from the opposite end is discharged back through the valve V3 to the reservoir 7. This procedure is reversed to actuate the levers 171 and 172 in opposite directions and this valve V3 is operated in the same manner as the valve V6 hereinbefore described.

Cutting oil pump

A cutting oil pump 175 (see Fig. 10) is mounted in a housing in the rear of the gear box wall and is driven by the shaft 157 through its gears 176 at a constant speed.

From the foregoing it will be seen that the present improvement results in the provision of a compact high speed single spindle machine in which the locking bolt for the tool turret is withdrawn, the turret indexed, the tool slides of the turret reciprocated, the top cross slide operated, the work chucked, the stock feed slide returned and the high and low speed clutches and spindle clutch are all operated hydraulically in a very efficient manner expeditiously to turn out the work.

It is to be understood that, by describing in detail herein any particular form, structure or arrangement, it is not intended to limit the invention beyond the terms of the several claims or the requirements of the prior art.

Having thus explained the nature of our said invention and described a way of constructing and using the same, although without attempting to set forth all of the forms in which it may be made or all of the modes of its use, we claim:

1. In an automatic screw machine, the combination of a rotary work spindle located substantially centrally lengthwise of the machine, means for rotating the spindle, an indexible tool turret having its axis below and in substantially the same plane as the axis of the work spindle and having reciprocating independently operated tool slides, means for reciprocating the slides, locking means for the tool turret comprising a disk having a plurality of lock bolt seats, the surface of said disk tapering toward each of said seats, a lock bolt cooperating therewith, means for controlling the locking means, and means for indexing the tool turret, said indexing means being operatively controlled by the locking means and gradually stopped thereby.

2. In a metal working machine having a rotary spindle and cooperating tool mechanism, a series of cross slides encircling said spindle, means for feeding bar stock through the spindle and including finger holding mechanism having a double toggle provided with a roller at the junction of the toggle levers, and a pair of relatively shiftable socketed members for receiving the opposite ends of said levers, the diameter of the roller being such that the distance between the opposing faces of said shiftable socketed members when shifted toward each other is but slightly greater than the diameter of the roller.

3. In a single spindle automatic screw machine, the combination of a framework comprising a series of housings, a rotary work spindle, means for rotating the spindle, an indexible tool turret having reciprocating independently operated tool slides, locking means for the turret, top and side cross slides encircling the spindle, means including high and low speed clutch mechanism for operating the side slides, and hydraulically operated means for indexing the turret, shifting the slides thereof, controlling the operation of the locking means, the top and side cross slides and the stock feeding and chucking means, all of the operating mechanisms for the spindle, the indexible turret and its locking means, the indexible tool slides, the top and side cross slides, and the stock feeding and chucking means including the hydraulic operating mechanisms being completely enclosed in the housings and not exposed to chips or parts cut off from the stock bars.

4. The machine of claim 3 in which the framework has a pan-shaped base carrying the entire machine and having an enlarged chip space under the turret slides with a clean out passage at the front end of the machine whereby the chips may be removed without stopping the machine.

5. An automatic single spindle screw machine comprising a base having at each end a housing-formed supporting frame and therebetween and spaced from one of said end housing supporting frames an intermediate housing-formed supporting frame, an indexible tool turret having tool slides thereon and supported by said spaced housing frames, turret indexing and locking mechanism in the end housing supporting frame that carries one end of the indexible tool turret, a rotary work spindle and operating means therefor supported in said intermediate housing frame, a series of encircling cross slide supports carried by said intermediate housing frame at the front thereof, stock feeding and chucking mechanism carried in the other end housing frame, and operating means for the various mechanisms of the machine also carried in said last housing frame.

6. The machine of claim 5 in which one end housing and the intermediate housing form a continuous supporting housing framework.

7. The machine of claim 5 in which the intermediate frame housing also has at one side thereof an auxiliary tool support.

8. The machine of claim 5 in which the opposed spaced housings have side chip guards therebetween protecting upwardly from the base.

9. The machine of claim 5 in which the opposed spaced housings have side chip guards therebetween projecting upwardly from the base and rigidly connecting the opposed housings.

10. The machine of claim 5 in which the base has a relatively large space under the indexible tool turret for the reception of chips and the end supporting frame housing adjacent thereto is arch-formed to provide a relatively large passage for the removal of the chips from the end of the machine whereby accumulated chips may be removed without stopping the machine.

11. The machine of claim 5 in which fluid operated means controls the unlocking and indexing of the turret slide, the independent operation of the tool slides of the turret at variable speeds, the control of one of the cross slides and the operation of the stock feeding and chucking means for the rotary spindle, all of said fluid operated means controlled by a part of the operating means in timed relation.

12. The machine of claim 5 in which the tool turret indexing and locking mechanism in the end housing supporting frame comprises hydraulically operated means.

13. The machine of claim 5 in which the tool turret indexing and locking mechanism in the end housing supporting frame comprises hydraulically operated means and in which the tool slides of the indexible turret are hydraulically and independently operated at variable speeds, all of said hydraulically operated means controlled by a part of the operating means in timed relation.

14. The machine of claim 5 in which one of the encircling cross slides is hydraulically controlled by means located within the intermediate housing.

15. The machine of claim 5 in which the stock feeding and chucking mechanism is operated by hydraulically operated means located within one of the housing frames.

16. The machine of claim 5 in which high speed or rapid traverse mechanism is provided for the

side cross slides and which, together with its operating means is located in a housing supporting frame spaced from the housing supporting frame carrying the tool turret and locking mechanism.

17. An automatic single spindle machine having at each end a housing-formed supporting frame and therebetween and spaced from one of said end frames and in juxtaposition to the other end frame an intermediate housing-supporting frame, a rotary work spindle supported in said intermediate housing frame, a series of cross slides carried at the front of said intermediate frame and encircling said spindle, operating means carried in the end frame juxtaposed to the intermediate frame for elements of the machine, an indexible slide supporting tool turret supported by said spaced frames, and turret indexing and locking means in the end frame that supports one end of the tool turret.

18. The machine of claim 17 in which means carried within the turret supporting end frame controls the locking means.

19. The machine of claim 17 in which means carried within the turret supporting end frame controls the locking means and includes hydraulically operated means.

20. The machine of claim 17 in which the means carried within the turret supporting end frame for indexing the turret includes hydraulically operated means.

21. The machine of claim 17 in which hydraulically operated means shifts the tool turret slides independently and at different speeds.

22. The machine of claim 17 in which the tool turret indexing means is operatively connected to and controlled by the locking means and gradually stopped thereby.

23. The machine of claim 17 in which hydraulically operated means controls the indexing of the turret and in which hydraulically operated means controls the locking means and also controls the hydraulically operated turret indexing means and gradually stops indexing thereof.

24. The machine of claim 17 in which hydraulically operated clutch controlled means is provided for rotating the spindle and in which the machine has hydraulically and spring controlled stock feeding means and also hydraulically controlled chucking means for the stock and hydraulically operated means for shifting the top tool slide at variable speeds, all of said hydraulically controlled means controlled by a part of the operating means in timed relation.

25. The machine of claim 17 in which means having a clutch is provided for rotating the spindle, fluid means is provided for controlling the operation of said clutch; fluid means is provided for controlling the turret locking mechanism and indexing the turret; fluid means is provided for independently operating the turret slides at different speeds; means is provided for operating the spindle cross slides including high and low speed clutch mechanism, fluid means for controlling said clutch mechanism and thereby the cross slides at different speeds, fluid means for operating the top slide at different speeds, stock feeding and chucking means for the spindle, and fluid means for operating the stock chucking means and controlling the return thereof, all of said fluid controlled means controlled by a part of the operating means in timed relation.

26. An automatic single spindle machine

adapted for use as a bar machine or as a chucking machine and comprising a convertible single rotary spindle operative at different speeds and including hydraulically operated clutch controlled

means for rotating said spindle, hydraulically operated work controlling means for the spindle, a series of top and side cross slides encircling the spindle, hydraulically operated means for operating the top slide, means for operating the side slides, hydraulically operated clutch control means for controlling the feed of the side slides, a hydraulically operated indexible tool turret provided with hydraulically operated tool slides operative at different speeds, locking means for the turret and hydraulically operated means for controlling a movement of said locking means and also the indexing of the turret, all of said operating mechanisms supported and enclosed in housings assembled to form a low-down compact machine, and all controlled by a part of the operating means in timed relation.

27. In an automatic screw machine, the combination of a rotary work spindle, means for rotating it, an indexible tool turret having reciprocating independently operated tool slides, fluid operated means for shifting the tool slides at variable speeds, means for fluidly indexing said turret, means for locking it in indexed position and comprising a lock bolt and a disk provided with a plurality of lock bolt seats, the surface of said disk tapering toward each of said seats, and fluid operated means automatically thrown into operation for controlling the lock bolt, the operation of said lock bolt operative to control the indexing means and the cooperation of the lock bolt and tapered surface of said disk effective gradually to stop operation of the indexing means.

28. The machine of claim 17 in which the locking means is operatively connected to and gradually stops the indexing means.

29. The machine of claim 5 in which said operating means includes hydraulic means located in said last housing frame.

30. The machine of claim 5 in which said operating means comprises a main driving motor and also includes hydraulic mechanism located in said last housing frame.

ALFRED E. DRISSENER.
KENNETH W. BARKINEN.
